TUMBLER

Jerome Lewis, New York, N.Y.
(84-86 Clifton Place, Brooklyn 38, N.Y.)

Filed Apr. 10, 1958, Ser. No. 50,420

Term of patent 14 years

(Cl. D36—8)

FIG. 1

FIG. 2

FIG. 3

Fig. 1 is a perspective view of a tumbler showing my new design;

Fig. 2 is a top plan view; and

Fig. 3 is a bottom plan view.

The ornamental insert is continuous around the entire tumbler.

I claim:

The ornamental design for a tumbler, as shown and described.
